COMBINED DOOR KNOB AND ESCUCHEON PLATE

Karl W. Kamb, Culver City, Calif., assignor to Beemak,
Inc., Culver City, Calif., a corporation of California

Filed Dec. 26, 1962, Ser. No. 72,963

Term of patent 14 years

(Cl. D50—3)

FIG. 1 is a front elevational view of a combined door knob and escutcheon plate embodying my new design; and

FIG. 2 is a side elevational view in partial section taken along the lines 2—2 of FIG. 1.

I claim:

The ornamental design for a combined door knob and escutcheon plate, as shown.
